BUTTONHOLE GUIDE FOR FACILITATING
LAYOUT OF BUTTONHOLES

Milton Heimlich, Larchmont, N. Y.

Application March 29, 1950, Serial No. 152,625

6 Claims. (CL. 33—174)

1

My present invention relates to a device for facilitating the lay-out of buttonholes.

It is a general object of the invention to provide an inexpensive and handy tool of simple construction, for use by dressmakers and tailors to aid in the proper preliminary laying out of buttonholes to be formed in a garment or the like.

It is necessary to make a buttonhole longer than the diameter of the button for which it is intended, in order to allow for free passage of the button through the buttonhole. This is due to the fact that as the hole is widened by passage of the button its length is decreased by an amount slightly less than the thickness of the button. The buttonhole length should therefore exceed the diameter of the button by an amount approximately equal to the thickness of the button. Since buttons differ widely both as to diameter and thickness, their corresponding buttonhole lengths must also differ to compensate for both dimensions.

The present tool not only enables one to determine quickly the proper lengths of buttonholes to compensate for button thicknesses, but serves also as a convenient means for marking the spacing between buttonholes.

More specifically, my invention lies in the provision of a tool which will automatically determine the length of a buttonhole needed for a given button, and which requires only one button gauging operation, i. e., one in which a single button measurement will yield the buttonhole length without the need for separately measuring both the diameter and the thickness of the button.

I achieve these objects, and such other objectives and advantages as may hereinafter appear or be pointed out, in the manner illustrated in the appended drawings, wherein:

Figure 1 is a plan view showing a tool constructed in accordance with my invention and shown in operative relation to a button;

Figure 2 is an elevational view of the tool, with the parts occupying the same positions as in Figure 1;

Figure 3 is a side elevation similar to Figure 2 but with a different button being gauged;

Figure 4 is an end view of the device with the button omitted, as viewed along the direction 4—4 of Figure 3; and

Figure 5 is a diagrammatic view showing the manner of application of the buttonhole guide to an illustrative lay-out of buttonholes.

The buttonhole guide illustrated herein comprises a flat relatively rigid strip or base member

2

10 which may be formed of any material suitable for use as a rule or for measuring purposes, such as metal, plastic, wood, etc. The strip is preferably thin having upper and lower surfaces 11 and 12, side edges 13 and end edges 14. One or more of these edges may be marked with divisions of length measurement as shown at 15.

At one end of the strip 10 there is formed a preferably fixed elevation 20 having an undercut face or surface 21. In fixed relation to the elevation 20 is a finger 25 which projects outwardly, i. e., laterally, preferably from the calibrated edge 13 of the strip, and having an index edge 23 which is preferably aligned with the zero marking of the scale 15 and the base or intersection line 22 of the inclined surface 21.

The strip 10 is provided with a longitudinal slot 16 having side walls 17 which are parallel to the edges 13. Disposed within the slot are separate slides 30 and 31. Each slide is preferably of resilient material, such as metal, formed of an initially flat strip and provided with a medial loop portion 32 which extends above the upper surface of the guide 10. Below the loop are neck portions 33 and a pair of foot portions 34 and 35 turned outwardly to lie adjacent to the undersurface 12 of the guide strip. Each slide is formed with an indexing edge on its foot portion 35. The indexing edge on the slide 30 is designated 36, and the corresponding edge on the slide 31 is designated 37.

Slide 31 constitutes an adjustable abutment intended to cooperate with the elevation 20, and may, for example, carry a member 38 cemented or otherwise secured to the slide in such manner as to present a flat surface 39 in opposition to the fixed and inclined surface 21. Member 38 is so connected to the slide 31 as to move therewith, and its surface 39 is aligned with the indexing edge 37.

The slide construction described may be simply fabricated from strip stock of resilient material by first stamping and forming the loop and neck portions; the foot portions may then be inserted 45 through slot 16, from the top; and the foot portions are then bent outwardly into their final positions. When thus formed and assembled each slide is freely movable along slot 16, the resilience of the loop portion exerting pressure outwardly against slot edges 17 through the neck portions 33 to hold the slide frictionally in any desired position.

The guide is used as follows: In order to determine the proper length of the buttonhole to be formed for any given button, the button is laid

on the upper surface of the guide near the elevation 20 and the slide 31 is pushed toward it until the button is snugly interposed between the inclined surface 21 and the upright surface 39. Where the surface 21 is formed at a 45° angle to the strip 10, an isosceles triangle is subtended between the button and the surfaces 21 and 11, in which triangle the two equal sides are equal to the thickness of the button (see Fig. 2). Therefore the length of the buttonhole measured between the indexing edges 23 and 37 is equal to the diameter of the button plus its thickness. If buttons of varying thickness are applied to the guide in the above manner, the lengths measured between edges 23 and 37 will correspondingly vary. Compare, for example, Figures 2 and 3 wherein the relative positions of the elements are indicated when the guide is applied first to a thick button A (Fig. 2) and then to a button B having the same diameter, but thinner (Fig. 3).

It has been found that placing the surface 21 at a 45° angle yields satisfactory results. However, other angles may be used if desired, to provide a different button-thickness compensatory adjustment.

The slide 30 is utilized as an index to the spacing between the holes. If, for example, in a garment C (Fig. 5), it is desired to form a row of buttonholes D, for a given size button A, and the buttonholes are to be spaced by a distance S, slide 30 is moved to a position in which the distance between its edge 36 and the fixed edge 23 is exactly S. The guide 10 is then laid on the cloth C with edge 23 at a selected starting point and the cloth is marked at edge 36. The guide is then lifted to shift edge 23 to the last-made mark, and the new location of edge 36 is marked, and so on. This procedure is repeated until the entire row of holes D, with spacings S, is completed.

The button A is then placed on the guide 10 and the slide 31 positioned against it, in the manner previously described, to determine the proper length L of the hole D. The button may then be removed and the guide applied to the cloth at each of the previously-made markings, as shown at the right, in Figure 5. The required and exact length L of each hole is then marked on the cloth or may be cut directly into the cloth, by cutting between finger edges 23 and 37. Having thus laid out the buttonholes on the material with the desired spacing and the exact length, each hole may be cut, sewn, and completed in the usual manner.

While I have described my invention as applied to the making of buttonholes it may be capable of use in other fields. It will also be understood that those skilled in the art may make modifications in the material, shape and details of the exemplified embodiment without necessarily departing from the scope and spirit of the appended claims.

Having thus described my invention and illustrated its use, what I claim as new and desire to secure by Letters Patent is:

1. A buttonhole guide comprising a base member, a fixed element having an overhanging surface projecting upwardly from said base member, a fixed indicating finger carried by and projecting from said base member adjacent to said fixed element, a movable element projecting upwardly

from said base member and provided with an indicating finger projecting in the same direction as said fixed finger, said movable element and finger being slidably carried by said base member so as to allow the engagement on said base member and between said projecting elements of buttons of varying diameter and thickness, the distance between said fingers varying in proportion to varying button diameters and also to varying button thicknesses whereby said distance serves to indicate the proper length of buttonhole required for the particular button engaged between said projecting elements.

2. A buttonhole guide as set forth in claim 1 wherein said overhanging surface is formed at an angle of substantially 45° to said base member.

3. A buttonhole guide comprising: a flat member for application to material in which a buttonhole is to be formed, a fixed element having an overhanging surface projecting upwardly from the upper surface of said flat member, a fixed indicating finger having an edge aligned with the lowermost edge of said element, a second element projecting upwardly from said flat member and provided with an upstanding surface facing toward said fixed element and an indicating finger having an edge aligned with said upstanding surface, said second element being slidably carried by said flat member so as to allow the engagement on said flat member and between said projecting elements of buttons of varying diameter and thickness, the space between said fingers indicating the proper length of buttonhole to be formed to compensate for buttons of varying thickness.

4. A buttonhole guide as described in claim 3 wherein said overhanging surface is formed at an angle of substantially 45° with the upper surface of said flat member.

5. A buttonhole guide as described in claim 3 wherein said indicating fingers project from one edge of the flat member and said edge is provided with length markings.

6. A buttonhole guide comprising: a flat strip, an inclined surface fixed to and extending from the upper surface of the strip near one end thereof for engaging one edge of a button, a fixed index finger adjacent to the inclined surface and projecting from an edge of the strip, an elongated slot in the strip parallel to said edge, and a slide movable in said slot and presenting a surface for engaging the opposite edge of the button, said slide having an indicating finger projecting beyond said edge of the strip.
